UNITED STATES PATENT OFFICE

169,701

BROODER HEATER

William Rusnak, Chicago, and Wilbert G. Stoll,
Evanston, Ill., assignors to Afco-Lite Corpora-
tion, Chicago, Ill.

Application November 5, 1951, Serial No. 17,286

Term of patent 7 years

(Cl. D12—2)

To all whom it may concern:

Be it known that we, William Rusnak and Wilbert G. Stoll, citizens of the United States, residing respectively at Chicago and Evanston, in the county of Cook and State of Illinois, have invented a new, original, and ornamental Design for a Brooder Heater, of which the following is a specification, reference being had to the accompanying drawing, forming a part thereof, in which:

Fig. 1 is a front elevational view of a brooder heater showing our new design;

Fig. 2 is a top plan view thereof; and

Fig. 3 is a bottom plan view thereof.

We claim:

The ornamental design for a brooder heater, substantially as shown.

WILLIAM RUSNAK.
WILBERT G. STOLL.
